(57) **CLAIM**

The ornamental design for a sculpting device, as shown and described.

DESCRIPTION

FIG. 1 is a front perspective view of a sculpting device showing my new design;

FIG. 2 is a rear perspective view thereof;

FIG. 3 is a front elevational view thereof;

FIG. 4 is a rear elevational view thereof;

FIG. 5 is a right side elevational view thereof with the left side elevational view being a mirror image of the right side elevational view;

FIG. 6 is a top view thereof; and,

FIG. 7 is a bottom view thereof.

The broken lines showing displaced sculptural fibers in the shape of indicia in FIGS. 1-7 are for the purpose of showing features that form no part of the claimed design.

1 Claim, 6 Drawing Sheets

FIG. 1
